UNITED STATES PATENT OFFICE.

WILLY PETERSSON, OF HAMBURG, GERMANY.

LIQUID METER.

Application filed September 12, 1923. Serial No. 662,259.

To all whom it may concern:

Be it known that I, WILLY PETERSSON, a citizen of the German Republic, and resident of No. 11 Forssmannstr., Hamburg, in the Republic of Germany, have invented a new and useful Improved Liquid Meter, of which the following is a specification.

The present invention relates to a liquid meter provided with an inlet and outlet valve alternately opened and closed by a float to control the admission of liquid to and its escape from a measuring chamber, a registering apparatus or counter being in operative connection with the valves and means being provided to prevent a premature actuation of the valves under the rise and fall of the float.

Special objects of the invention are to render more efficient, serviceable and durable in operation devices of the kind referred to.

With these ends in view the invention consists in the novel combination, arrangement and adaptation of parts, all as more fully hereinafter described, shown in the accompanying drawings and then specifically set out in the appended claim.

In the drawing is shown by way of example one mode of carrying into practice the invention, the figure representing a vertical section through the improved liquid meter.

The measuring chamber 1 preferably in the form of a cylinder or barrel is connected by the flange 2 to the top edge of a lower collecting chamber 3, so that it extends into the latter as shown. At the top end, the measuring chamber 1 is closed by the bottom 4 of a casing 5 secured to the flange 2.

Centrally in regard to the measuring chamber 1 a vertical valve stem 6 is arranged, which is conically shaped at its lower end to form a needle valve 7 in connection with the valve seat 8 in the bottom 4 of the measuring chamber 1. The upper end of the valve stem 6 extends through and is rectilinearly guided in a hole 9 in the top

55 The liquid to be measured is supplied to the chamber 1 by a pipe 10 in connection with the casing 5, communication between this pipe 10 and the measuring chamber 1 being established and interrupted by means of the valve 11 having its seat in a hole of the top 4. This inlet valve 11 is in operative

connection with the valve stem 6 of the outlet valve 7. As shown in the drawing the inlet valve 11 is acted upon by a two armed lever 13 having its fulcrum provided by a pin seated in a bracket 12 fast to the lower surface of the top 4. The second arm of the lever 13 is bifurcated and engages a pin 14 fast to and projecting from the valve stem 6 as shown.

The valve stem 6 acts as a guide upon which an annular float 15 is slidably positioned in such a manner as to move longitudinally of the measuring chamber 1 as the level of the liquid therein rises and falls.

Above the needle valve 7 the valve stem 6 is hollow and serves to accommodate and guide a rod 26, which projects beyond the top end of the valve stem. Above and below the float 15 the hollow valve stem 6 is provided with slot openings. Pins 16 and 17 fast to the rod 26 project through these slot openings so that they limit the rise and fall of the float 15 on the valve stem 6.

In descending the float 15 contacts with the pin 17 and exerts sufficient pressure to move the rod 26 downwardly inside the valve stem 6. This downward movement of the rod 26 serves for actuating a registering apparatus or counter in a manner to be fully described later on.

After the rod 26 has reached the limit of its downward movement inside the valve stem 6 the continued pressure of the descending float 15 on the pin 17 forces the valve stem 6 downward until the needle valve 7 reaches its seat 8 and cuts off the escape of liquid from the measuring chamber 1. This downward movement of the valve stem 6 is translated by the operative connection between the pin 14 and the two armed lever 13 into an upward movement of the inlet valve 11 so that the supply of liquid from the pipe 10 to the measuring chamber 1 is established while the outlet valve 7 is closed.

Admission of liquid to the measuring chamber 1 continues until the rising level lifts the float 15 sufficiently to contact with the pin 16, thereby raising the rod 26 and finally the valve stem 6. By raising the rod 26 and the valve stem 6 the outlet valve 7 is opened, whereas the inlet valve 11 is closed, the two armed lever 13 by its operative connection with the valve stem 6 swinging back into its initial position allowing the valve 11 to automatically close against its seat and

thus to cut off the supply of liquid to the measuring chamber 1.

The pipe 10 effects connection with any desired reservoir holding liquid to be drawn off; from the collecting chamber 3 a pipe 18 leads to the place of destination of the liquid.

The amount of liquid periodically admitted to and passing through the measuring chamber 1 by the alternate action of the inlet and outlet valves 11 and 7 may be regulated according to desire or requirement.

In order to register or count the number of charges passed through the measuring chamber 1 the following novel arrangement is provided.

Inside the casing 5 a spring motor 19 is housed which may be wound up periodically by means of an externally accessible key in the usual manner. The spring motor 19 drives a train of wheels 20, the last wheel of which acts as an escapement being formed by a disc 21 having a locking tooth 22 on its circumference. An anchor 24 oscillating on a pin 23 partly surrounds the circumference of the disc 21, arresting the rotation of the latter by means of pallets at its two extremities which alternately engage the tooth 22. Each actuation of the anchor 24 liberates the disc 21 to perform a half revolution whereupon it is arrested again by the pallet on the second extremity of the anchor 24 engaging the tooth 22. The anchor 24 has a lever arm 25 projecting beyond the pin 23, said lever arm being in operative connection with the rod 26 at the upper end issuing from the valve stem 6. The upward and downward movement of the rod 26 caused by the rise and fall of the float 15 oscillates the anchor 24, so that the disc 21 is liberated to perform a half revolution during the upward as well as during the downward movement of the rod 26. A lever arm 27 in fixed connection with the anchor 24 is coupled to a pitman rod 28 which is pivotally connected to a crank 29 for actuating the registering apparatus or counter during each complete revolution of the disc 21. The registering apparatus or counter of any well known and appropriate construction may be inspected through a window 31 in the lid of the casing 5.

In order to prevent a premature downward movement of the valve stem 6 resulting in a premature closure of the outlet valve 7 when the float 15 descends, a two armed lever 33 is pivoted around a pin 32 in the casing 5, said lever being bifurcated at one end and engaging with this end a pin 34 projecting from the valve stem 6, whereas the other end of this lever abuts against a cam 35 in fixed connection with

the escapement 21. During each complete revolution of the escapement 21 this cam 35 acts on the lever 33 in such a manner that the valve stem 6 is retained in its elevated position while the float 15 starts its descent with the fall of the level in the measuring chamber 1. When the rod 26 is sufficiently moved downwardly by the float 15 contacting with the pin 17 to start the rotation of the disc 21 under the influence of the spring motor 19, the cam 35 partaking in this rotation liberates the lever 33 at the proper moment for closing the outlet valve 7.

The improved liquid meter is specially adapted for use with petrol or gasoline tanks, it may however be utilized in connection with any other liquid to be drawn off in predetermined quantities.

I wish it to be distinctly understood, that I do not limit myself to the precise construction shown, seeing that various modifications may be carried out in the adaptation of my improved liquid meter to the several kinds of application and I therefore reserve the right to all such modifications that properly fall within the scope of the following claim.

What I do claim as my invention and desire to secure by Letters Patent is:—

A liquid meter comprising an upwardly opening measuring chamber provided with an outlet, a register casing adapted to be secured to the open end of said chamber to form a top therefor and provided with an inlet leading to said chamber, valves for controlling said openings, means connecting said valves whereby to open one valve and close the other to alternately fill and empty the measuring chamber, a float in said chamber, spring impelled mechanism in the register casing, gearing adapted to be driven by said mechanism and including an escapement disc and cam adapted to rotate in unison, means connected to the valve connecting means and engaging the cam for operating the valves upon rotation of said cam, means in engagement with said disc to control the rotation thereof, means connected to the last named means adapted to be operated by the float as it rises and falls with the liquid level in the measuring chamber for controlling the rotation of the disc and a register in the casing adapted to be driven by the gear train for indicating the volume of liquid passing through the meter.

In witness whereof I have hereunto signed my name this 31st day of July 1923, in the presence of two subscribing witnesses.

WILLY PETERSSON.
